(57) **CLAIM**

The ornamental design for a protective case for a foldable smartphone, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a top, left, front perspective view of a protective case for a foldable smartphone showing a first embodiment of the new design in a fully folded condition;

FIG. 2 is a right, rear, bottom perspective view of the invention illustrated in FIG. 1;

FIG. 3 is a front view of the invention illustrated in FIG. 1;

FIG. 4 is a rear view of the invention illustrated in FIG. 1;

FIG. 5 is a left side view of the invention illustrated in FIG. 1;

FIG. 6 is a right side view of the invention illustrated in FIG. 1;

FIG. 7 is a top view of the invention illustrated in FIG. 1;

FIG. 8 is a bottom view of the invention illustrated in FIG. 1;

FIG. 9 is a top, left, front perspective view of the invention illustrated in FIG. 1, showing an environmental foldable smartphone in a fully folded condition in broken lines;

FIG. 10 is a front perspective view of the invention of FIG. 1 showing the new design in a fully unfolded condition;

FIG. 11 is a rear perspective view of the invention illustrated in the condition illustrated in FIG. 10;

FIG. 12 is a front view of the invention illustrated in the condition illustrated in FIG. 10;

FIG. 13 is a rear view of the invention illustrated in the condition illustrated in FIG. 10;

FIG. 14 is a left side view of the invention illustrated in the condition illustrated in FIG. 10;

FIG. 15 is a right side view of the invention illustrated in the condition illustrated in FIG. 10;

(Continued)

FIG. 16 is a top view of the invention illustrated in the condition illustrated in FIG. 10;
 FIG. 17 is a bottom view of the invention illustrated in the condition illustrated in FIG. 10;
 FIG. 18 is a front perspective view of the invention illustrated in the condition illustrated in FIG. 10, showing an environmental foldable smartphone in a fully unfolded condition in broken lines;
 FIG. 19 is a top, left, front perspective view of a protective case for a foldable smartphone showing a second embodiment of the new design in a fully folded condition;
 FIG. 20 is a right, rear, bottom perspective view of the invention illustrated in FIG. 19;
 FIG. 21 is a front view of the invention illustrated in FIG. 19;
 FIG. 22 is a rear view of the invention illustrated in FIG. 19;
 FIG. 23 is a left side view of the invention illustrated in FIG. 19;
 FIG. 24 is a right side view of the invention illustrated in FIG. 19;
 FIG. 25 is a top view of the invention illustrated in FIG. 19;
 FIG. 26 is a bottom view of the invention illustrated in FIG. 19;
 FIG. 27 is a top, left, front perspective view of the invention illustrated in FIG. 19, showing an environmental foldable smartphone in a fully folded condition in broken lines;
 FIG. 28 is a front perspective view of the invention of FIG. 19 showing the new design in a fully unfolded condition;
 FIG. 29 is a rear perspective view of the invention illustrated in the condition illustrated in FIG. 28;
 FIG. 30 is a front view of the invention illustrated in the condition illustrated in FIG. 28;
 FIG. 31 is a rear view of the invention illustrated in the condition illustrated in FIG. 28;
 FIG. 32 is a left side view of the invention illustrated in the condition illustrated in FIG. 28;
 FIG. 33 is a right side view of the invention illustrated in the condition illustrated in FIG. 28;
 FIG. 34 is a top view of the invention illustrated in the condition illustrated in FIG. 28;
 FIG. 35 is a bottom view of the invention illustrated in the condition illustrated in FIG. 28;
 FIG. 36 is a front perspective view of the invention illustrated in the condition illustrated in FIG. 28, showing an environmental foldable smartphone in a fully unfolded condition in broken lines.
 FIG. 37 is a top, left, front perspective view of a protective case for a foldable smartphone showing a third embodiment of the new design in a fully folded condition;
 FIG. 38 is a right, rear, bottom perspective view of the invention illustrated in FIG. 37;
 FIG. 39 is a front view of the invention illustrated in FIG. 37;
 FIG. 40 is a rear view of the invention illustrated in FIG. 37;
 FIG. 41 is a left side view of the invention illustrated in FIG. 37;
 FIG. 42 is a right side view of the invention illustrated in FIG. 37;
 FIG. 43 is a top view of the invention illustrated in FIG. 37;
 FIG. 44 is a bottom view of the invention illustrated in FIG. 37;
 FIG. 45 is a top, left, front perspective view of the invention illustrated in FIG. 37, showing an environmental foldable smartphone in a fully folded condition in broken lines;

FIG. 46 is a front perspective view of the invention of FIG. 37 showing the new design in a fully unfolded condition;
 FIG. 47 is a rear perspective view of the invention illustrated in the condition illustrated in FIG. 46;
 FIG. 48 is a front view of the invention illustrated in the condition illustrated in FIG. 46;
 FIG. 49 is a rear view of the invention illustrated in the condition illustrated in FIG. 46;
 FIG. 50 is a left side view of the invention illustrated in the condition illustrated in FIG. 46;
 FIG. 51 is a right side view of the invention illustrated in the condition illustrated in FIG. 46;
 FIG. 52 is a top view of the invention illustrated in the condition illustrated in FIG. 46;
 FIG. 53 is a bottom view of the invention illustrated in the condition illustrated in FIG. 46; and,
 FIG. 54 is a front perspective view of the invention illustrated in the condition illustrated in FIG. 46, showing an environmental foldable smartphone in a fully unfolded condition in broken lines.
 The broken lines in the drawings depict environment, or portions, of the protective case for a foldable smartphone that form no part of the claimed design.
